CLAIM

The ornamental design for a weight plate, as shown and described.

DESCRIPTION

FIG. 1 is a top perspective view of a first embodiment of a weight plate showing my new design, the bottom perspective view being a mirror image;

FIG. 2 is a top plan view thereof;

FIG. 3 is a bottom plan view thereof which is a mirror image of the top plan view;

FIG. 4 is a left side elevational view thereof;

FIG. 5 is a right side elevational view thereof which is a mirror image of the left side elevational view;

FIG. 6 is a front elevational view thereof;

FIG. 7 is a rear elevational view thereof which is a mirror image of the front elevational view;

FIG. 8 is a top perspective view of a second embodiment of the weight plate, the bottom perspective view being a mirror image;

FIG. 9 is a top plan view thereof;

FIG. 10 is a bottom plan view thereof which is a mirror image of the top plan view;

FIG. 11 is a left side elevational view thereof;

FIG. 12 is a right side elevational view thereof which is a mirror image of the left side elevational view;

FIG. 13 is a front elevational view thereof; and,

FIG. 14 is a rear elevational view thereof which is a mirror image of the front elevational view.
